UNITED STATES PATENT OFFICE.

WALTER B. FOWLER, OF LAWRENCE, MASSACHUSETTS.

REGULATING-DAMPER.

1,072,323.

Specification of Letters Patent.

Patented Sept. 2, 1913.

Application filed December 6, 1912. Serial No. 735,278.

To all whom it may concern:

Be it known that I, WALTER B. FOWLER, citizen of the United States, and resident of Lawrence, county of Essex, State of Massachusetts, have invented certain new and useful Improvements in Regulating-Dampers, of which the following is a specification.

This invention relates to regulating dampers of the type disclosed in Letters Patent of the United States No. 984,550, granted to me February 21, 1911, and is intended to render more perfect and delicate the action of such dampers beside facilitating their adjustment for different conditions of service.

In the accompanying drawings, Figure 1 is a side elevation illustrating the proper form of embodying the present invention; Fig. 2 is a front elevation thereof slightly broken away; and Fig. 3 is a plan view.

According to the form of my invention illustrated in the drawings, I employ a casing *a* preferably of cast iron, similar to the casing shown in my aforesaid patent. This casing is open on one side, the edges of said side projecting inwardly slightly to form a continuous flange *a'* to overlap the edge portion of the damper *b*.

The damper *b* is preferably made of sheet metal, and is riveted or otherwise secured to a supporting bar or axis *b'* whose ends rest on the ledges *a*² for pivotal support, said supporting bar being provided intermediate of the fulcrum or supporting points with an arm or lever *b*² intended to carry the adjustable counter-weight *c*. This adjustable counter-weight *c* is made to extend both forward and back transversely of the pivotal axis of the damper, and is shifted trans-

versely in order to vary, to any desired extent, its position according to the degree of counter-balance effect desired. To this end the counter-weight is made of an elongated bar longitudinally slotted to receive a binding screw *c'* which clamps it directly to the arm *b*². At this point the arm *b*² is provided with an elongated block or lug *b*³ which fits easily into the slot so as to prevent any pivotal or turning movement of the counter-weight *c* in relation to the supporting arm *b*², this integral lug serving as a guide to maintain a permanent angular relationship between the counter-weight and the arm.

Since the smoke pipes of some heaters carry a stronger draft than others, it is de-

sired that the regulator for any given smoke pipe be easily set to the proper predetermined position, normally demanded by the conditions of the draft to which it is applied. However, it is also desirable in order to expedite the action of the draft when the fire is low, to temporarily shift the position of the counter-balance. To meet these conditions the counter-balance has been made not only adjustable in the manner described, but is also further provided with an adjustable gage *d* consisting of a wire rod passed through one end of the member *c*, so as to project into the interior slot, said rod being hooked at the outer end in order to be more easily gripped, and being adjustably held in place by means of the thumb-screw *d'*.

In practice the attendant sets the gage member *d* to that predetermined position which he finds appropriate to normal service on the particular heater, and then when starting up the fire quickly the counter-balance may be shifted to the rear of the damper axis as far as desired to insure its remaining closed even under a strong draft. When the fire has burned up to a sufficient degree of intensity, the counter-balance is then shifted forward until the gage member *d* abuts against the arm *b*², thus involving no delay or trouble when securing the proper adjustment for normal service.

It is, of course, intended that the casing *a* is attached directly to the smoke pipe *o*, and that in actual operation when the draft becomes too strong in the smoke pipe, it automatically opens or draws in the damper *b*, so as to admit the outside air and check the draft. As the fire dies down the force of the draft lessens and the counter-balance tends to return the damper to closed position, thus tending once more to strengthen the draft and increase combustion.

I have found that by locking the counter-balance midway of the fulcrum supports, the damper is much more sensitive to slight variations in the draft than when the counter-balance is carried on one end of the damper axis, as in my former Letters Patent. Moreover, by using an elongated bar overhanging each side of the axis, I can get a greater range and delicacy of adjustment.

To increase the range and effectiveness for special conditions, I add a detachable weight-piece *c* screwed to one end of the counter-balance weight, which may be removed if found to be unnecessary for any

particular location. This dispenses with the need of making different sizes of counter-balance plates.

What I claim is:

- 5 1. A draft-regulating damper embracing in its construction a casing open at one side, a damper pivotally mounted to close said open side, a projecting weight-carrying arm or lever projecting from said damper, an
- 10 elongated counter-balance plate extending beyond said arm transversely on either side of the pivotal axis and a clamping nut carried by the supporting lever passing through the slot in said counter-balance in order to
- 15 adjustably clamp the counter-balance plate to the lever, substantially as described.
2. A draft-regulating damper embracing in its construction a casing open at one side, a swinging damper pivotally mounted to
- 20 close said open side and having a projecting weight-carrying lever, a slotted counter-balance plate mounted transversely to the axis of said damper and adjustably held to said lever by a slot and screw connection, a gage
- 25 member arranged to limit the adjustable movement of the counter-balance plate in relation to the supporting lever, substantially as described.

3. A draft-regulating damper embracing in its construction a casing provided with an open side, a swinging damper suspended to close said open side, a weight-carrying lever secured to said damper between the fulcrum points of support, a counter-weight adjustably clamped to said lever and shiftable transversely to the axis of said damper, and a gage for limiting the shifting movement of said counter-weight at a predetermined point, substantially as described.

4. A damper regulator embracing in its construction a casing, a damper swingably mounted thereon, a weight-carrying arm, an elongated longitudinally slotted plate, means for detachably clamping said slotted plate transversely of the damper axis, an adjustable gage member for limiting the adjustment of said counter-balance at a predetermined point and means for holding said gage member in its various positions, of adjustment, substantially as described.

In witness whereof, I have subscribed the above specification.

WALTER B. FOWLER.
